[57] CLAIM

The ornamental design for a combined twin-nibbed marker and level as shown and described.

DESCRIPTION

FIG. 1 is a perspective view of a combined twin-nibbed marker and level showing my new design;

FIG. 2 is a front elevational view;

FIG. 3 is a side elevational view, the opposite side and rear views being identical thereto; and

FIG. 4 is an end elevational view, the opposite end being a mirror image thereof.

FIG. 1.

FIG. 2.

FIG. 3.

FIG. 4.
